US0D1053284S

(12) **United States Design Patent** (10) **Patent No.:** **US D1,053,284 S**
(45) **Date of Patent:** **** Dec. 3, 2024**

(54) **LEG MUSCLE EXERCISER**

(71) Applicant: **Yonghua Liu**, Ji'an (CN)

(72) Inventor: **Yonghua Liu**, Ji'an (CN)

(**) Term: **15 Years**

(21) Appl. No.: **29/945,930**

(22) Filed: **Jun. 5, 2024**

(51) **LOC (14) Cl. 21-02**

(52) **U.S. Cl.**

USPC **D21/670**

(57) **CLAIM**

The ornamental design for a leg muscle exerciser, as shown and described.

DESCRIPTION

FIG. 1 is a front, top and left side perspective view of a leg muscle exerciser showing my new design;

FIG. 2 is a front, bottom and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines show the features of the leg muscle exerciser that form no part of the claimed design.

1 Claim, 8 Drawing Sheets
